UNITED STATES PATENT OFFICE

2,467,183

ELECTRICAL TROLLEY EQUIPMENT

Burtis W. Benbow, Benbow, Calif.

Application May 1, 1945, Serial No. 591,303

4 Claims. (Cl. 191—35)

1

This invention relates generally to electrical trolley assemblies or apparatus such as are used with movable electrical contacting devices for supplying electrical current to electrical equipment such as cranes, hoists, light electric locomotives and the like.

In apparatus of the above type it is common practice to utilize extended trolley conductors of suitable size and supported at intervals by suitable insulators. In the majority of installations the cables are bare and workmen are exposed to the hazards of accidental contact. It has been proposed to protect the conductors against accidental contact by the use of insulating shrouding, with the shrouding formed in such a manner as to permit continuous electrical contact. A novel shrouded conductor of this type is disclosed for example in my Patent No. 2,255,874. Certain problems are encountered in the installation of such equipment, particularly with respect to feeding current to the conductor at one or more points in order to insure current to the motors of the hoist, crane or other appliances without excessive voltage drop.

It is an object of the invention to provide apparatus of the above type incorporating novel means for feeding current to the insulated trolley conductor at one or more points.

A further object of the invention is to provide an assembly of the above character particularly adapted for use in conjunction with a conductor of the type disclosed in my Patent 2,255,874, where the insulating sheath for the conductor is interrupted on one side by a series of spaced recesses.

Additional objects and features of the invention will appear from the following description in which the preferred embodiment has been set forth in detail in conjunction with the accompanying drawing.

Referring to the drawing:

Fig. 1 is a plan view of equipment incorporating the invention and particularly a plan view of the equipment as shown in Fig. 2.

Fig. 2 is a side elevational view of the equipment as shown in Fig. 1.

Fig. 3 is an end view of the equipment shown in Fig. 1 with the trolley assembly shown in cross section.

Fig. 4 is a cross-sectional view taken on the line 4—4 of Fig. 2.

Fig. 5 is a cross-sectional view on an enlarged scale taken on the line 5—5 of Fig. 2.

Fig. 6 is a side elevational view of the equipment as shown in Fig. 5 with the forward half of the housing removed and with certain parts in section.

Fig. 7 is a cross-sectional view taken on the line 7—7 of Fig. 6.

The apparatus illustrated in the drawing con-

2

sists generally of a pair of aligned assemblies 10a and 10b, between which is interposed the assembly 11. A common trolley cable or conductor 12 extends through the aligned assemblies.

Each of the assemblies 10a, 10b consists in this instance of an insulating sheath 13 disposed about the conductor 12, and formed of suitable insulating material such as vulcanized natural or synthetic rubber having a fair degree of resiliency. One side (the upper side in this instance) of sheath 13 is attached to a mounting or backing strip 14, which can be formed in the manner disclosed in my copending application Serial No. 569,784, filed December 26, 1944. Briefly, the backing strip is made of sheet metal bent to a generally T-shaped cross section as shown in Figure 4, and with edges 16 crimped upon ribs 17 formed on the rubber sheath 13. The central rib 18 of the backing strip is formed of metal doubled upon itself as illustrated, and the substantially flat parallel surfaces or shoulders 19 formed on opposite sides of the rib 18, provide trackways to be engaged by guide rollers or wheels of a traveling contacting device, as disclosed in the aforesaid application Serial No. 569,784.

That side of the rubber sheath 13 opposite from the side attached to the backing strip 14 (the lower side of Figure 3), is interrupted by a series of regularly spaced recesses 21 in the manner disclosed in said application Serial No. 569,784, to permit access for making electrical contact with the lower side of the conductor 12.

These recesses are separated by bar-like teeth 22 of insulating material, formed like the teeth of a gear rack and integral with the main body of the sheath 13. A sheath formed in this manner is adapted to cooperate with a type of traveling contacting device such as shown in my Patent 2,255,874, namely one employing an endless chain made up of conducting links provided with teeth adapted to enter the recesses for making electrical engagement with the trolley wire.

The assembly 11, interposed between assemblies 10a and 10b, can consist of a conducting strip 26 made of suitable material such as copper or bronze, normally disposed in a plane coincident with the axis of conductor 12. Assuming that the apparatus is installed with the recesses 21 faced downwardly, the strip is in a vertical plane. The lower end of strip 26 is suitably electrically connected to the conductor 12, preferably by means permitting quick application without soldering. For this purpose the lower end of the strip is provided with a spring clip consisting of a pair of spring jaws 27 secured as by means of rivets 28 and solder to the strip 26. The jaws 27 are dimensioned and proportioned so that they must

be sprung outwardly to cause the same to be positioned on opposite sides of the conductor 12, as shown in Figure 5. In making an installation attachment of the strip can be accomplished simply by forcing the strip 26 downwardly upon the conductor 12. A terminal block 29 is attached to the upper end of strip 26 and this block has an opening 31 to receive the current feed cable 32. Suitable means such as clamping screws 33 insures a good grip and good current contact between the cable and terminal box 29.

That part of the conductor extending between assemblies 10a and 10b, and also the strip 26, are enclosed within a housing 34 of insulating material, such as a molded plastic like phenolic condensation material known as "Bakelite." Preferably this housing is made in two halves 34a, 34b, which are normally held together by screws 36. The lower portion 37 of the housing is formed to such width as to continue the side contour of the insulating sheath 13 of the assemblies 10a and 10b. Shoulders 38 are provided by portion 37 to provide a continuation of the trackways 19. Each housing part is also provided with lower studs 39 whereby when the two parts are assembled these studs underlie the conductor 12, and in effect form teeth corresponding to and having substantially the same spacing as the teeth 22 for the rubber sheath 13.

To provide a simple and effective means for making mechanical attachment between assembly 11 and the assemblies 10a, 10b, each housing part is provided with a projecting metal tab 41 dimensioned to fit within the adjacent end of the backing strip rib 18. In addition I provide a pair of locking keys 42, which are held in place by the spring retaining clips 43. Each of the keys 42 is provided with a lug or tab 44, engaging within a recess 46 formed in the housing 34, and also with a lug or tab 47 extending into the rib of the adjacent backing strip through a slot 48. The retaining clip 43 is made of spring sheet metal bent substantially U-shaped, with inturned lower edges 49 whereby when it is forced over the locking key 42 and the adjacent rib 18, its lower edges are accommodated and retained within the grooves 51, which are formed along the base of the rib 18.

Use of the invention can be described as follows: The assemblies 10a, 10b are attached by suitable brackets to an adjacent supporting structure, such as the bridge of a crane, whereby a traveling contacting device such as of the type described in my aforesaid patent, may operate along the length of the same. The wheels of this contacting device operate along the trackways 19 and across the trackways or shoulders 38 of the interposed assembly 11. Current is fed to the trolley conductor from the exterior conductor 32 with a negligible voltage drop because of the relatively low resistance afforded. My invention greatly facilitates making installations because it is a relatively simple matter to install the assembly 11 between two adjacent aligned assemblies 10a, 10b. In making such an installation it is only necessary to first apply the conducting strip 26 in the manner previously described, with the spring jaws 27 gripping the conductor 12, after which the two parts of the insulating housing 34 are applied one after the other, with the tabs 41 being inserted into the ribs 18. Thereafter the locking keys 42 are applied and retained in place by application of the spring clips 43. The exterior

current cable 32 can now be attached to the terminal block 29.

I claim:

1. In electrical trolley apparatus, an extended trolley conductor, an insulating sheath serving to protect the conductor against accidental contact, a backing strip attached to the upper side of the sheath and serving as a mounting for the same, said strip forming a pair of parallel trackways adapted to be engaged by guide wheels of a traveling contacting device, said strip and said sheath being interrupted by a gap, a vertical conductor strip located within the gap, the lower end edge of the strip being electrically connected to the conductor in such a manner as to leave the lower side of the conductor unobstructed for contact with a movable electrical contacting device, an insulating housing for the strip and for that portion of the conductor extending across said gap, said housing providing trackways in alignment with the aforesaid trackways of said backing strip, said last named trackways being disposed on opposite sides of said strip.

2. Apparatus as in claim 1 in which both said insulating sheath and said insulating housing are provided with spaced recesses extending through the lower side of the same for access to the trolley conductor, said recesses being spaced apart by teeth or bars of insulating material.

3. Apparatus as in claim 1 in which means is provided for releasably locking the end portions of the insulating housing to the adjacent backing strips.

4. In electrical trolley apparatus, an extended trolley conductor, an insulating sheath serving to protect the conductor against accidental contact, a backing strip attached to the upper side of the sheath and serving as a mounting for the same, said strip being formed to provide a rib and a pair of parallel trackways on opposite sides of the rib and adapted to be engaged by guide wheels of a traveling contacting device, said strip and said sheath being interrupted by a gap, a vertical conductor strip located within the gap and in a plane corresponding to the plane of said rib, the lower end edge of the strip being electrically connected to the conductor in such a manner as to leave the lower side of the conductor unobstructed for contact with a movable electrical contacting device, an insulating housing for the strip and for that portion of the conductor extending across the gap, said housing providing trackways in alignment with the aforesaid trackways of said backing strip, the portion of the housing on opposite sides of the strip forming a continuation of and being in alignment with said rib.
